ADVERTISING FIXTURE

Filed July 30, 1931

UNITED STATES PATENT OFFICE

LIONEL W. SHEPARDSON, OF TOLEDO, OHIO

ADVERTISING FIXTURE

Application filed July 30, 1931. Serial No. 553,976.

My invention has for its object to provide a fixture for use in public places, which will be useful and have a unique artistry and, at the same time, display desired advertising material. Another object of my invention is to provide a construction whereby advertising placards may be easily substituted for each other without disturbing the fixture or its parts.

The invention may be contained in structures that vary in their details of construction and, to illustrate a practical application of the invention, I have chosen an advertising fixture that embodies the invention, and shall describe it hereinafter. The fixture selected for purpose of illustration is shown in the accompanying drawings.

Fig. 1 illustrates a perspective view of the fixture. Fig. 2 illustrates a transverse view 20 of the upright structure. Fig. 3 illustrates a view taken on the plane of the line 3—3 shown in Fig. 2. Fig. 4 illustrates one of the wedges used in the stand of the fixture.

The fixture 1 chosen for purposes of illustration may have a suitable base 2 which may be decorated by bas relief, such as at 3. The base may have a pen or pencil support 4. A hollow pipe standard 5 is supported on the base 2. The pipe standard 5 may support, at its upper end, a conventional lamp socket and bulb 6, having a shade 7. The wires 9 may extend through the pipe standard 5 from the lamp socket to a source of electrical energy. Thus the lamp may be positioned to throw a light on the advertising matter below it.

The display case 10 may be formed of wood or sheet metal. The display case 10 has a back board 11. The back board 11 is formed 40 to have a central groove 12. Flange portions 13 are located along each side of the groove 12 and extend the entire length of the groove. The board 11 is held in an upright position on the pipe standard 5 by means of a sheet metal shell 15.

The sheet metal member 15 is channel shaped having outwardly extending flanges, or lips, 16, along opposite edges. The lips 16 are adapted to slide under the flange portions 13 of the groove 12 and to be held

therein. A pair of fillers, or wedges 20, having semi-cylindrical grooves 21, are formed to fit about the pipe standard 5 and fit within the casing member 15 so as to press the walls of the casing member 15 outwardly 55 and the lips 16 into engaging relation with the flanges 13. The lower ends 22, of the filler members 20, may have a wedge shape to insure a desirable tight fit about the pipe standard. Thus, the back board 11 is supported in an upright position as against movement of the fixture and effectively displays the advertising placards carried by it.

The advertising placards are supported on the back side of the back board by means of a frame 25 which extends around the edges of the back side of the back board. In order to allow for insertion of glass plate 28, or other equally transparent sheet, between the frame and back board, the back board may 70 have a raised portion 26 about three of its side edges. The frame 25 may be secured to the raised portion so that the edges of the frame extend slightly inwardly, forming a ledge 27 which will hold the glass in place. 75 One of the side edges of the back board does not have a raised portion, and thereby forms a slot 30 in combination with the back board and frame through which the glass plate 28, and advertising material 31, may be withdrawn or inserted.

The front side of the back board has two separate displays 35 and 36, both being substantially the same in construction. The display 35 is held in place by means of a frame 37 which extends about the edges of the front side of the back board and along the side of the casing member. Three sides of the frame 37 are fixed to a raised portion 38 on the front side of the back board and extend slightly inward to form a ledge 39 for retention of a glass plate 40. The upper end of the frame bridges the two side raised portions to form a slot 41. The slot 41 is adapted to receive the glass plate 40 and permits of insertion of advertising placards 42.

The shell 15 may be provided with a display unit 50. The front of the casing member may be provided with a raised portion 51 which extends around its top side edge and 100

bottom. The frame 52 may be fixed as by soldering so that it extends slightly over the edge of the raised portion 51 to form a ledge 53 for maintaining the glass plate 54 in position. One side edge of the casing member is bridged by the frame 52 to form a slot 55 through which the glass 54 and such advertising placards 56, as may be desired, may be inserted. Thus, it will be seen by my invention, I utilized substantially all the space about the pedestal for advertising purposes and, at the same time, provided a decorative lamp fixture, that may be readily assembled and the advertising material may be readily replaced.

I claim:

In an advertising fixture, a base, a pedestal secured to the base, a supporting board, frames secured to opposite sides of the supporting board and having edge portions located in spaced relation for the receipt of advertising material therein and forming slots located between the frame and the supporting board at the edges of the supporting board, the supporting board having inwardly extending flange parts and a sheet metal shell surrounding the pedestal and having outwardly extending flange parts for engaging the inwardly extending flange parts of the supporting board, blocks insertible within the shell and located intermediate the sides of the shell and the pedestal to force the said flanges into engaging relation, the shell having a frame, the frame having parts located in spaced relation with respect to the shell for receiving and retaining advertising sheet material.

In witness whereof I have hereunto signed my name to this specification.

LIONEL W. SHEPARDSON.
